DESIGN FOR AN ASHTRAY

William E. Mackelfresh, Jr., Chicago, Ill., assignor to Owens-Illinois Glass Company, Toledo, Ohio, a corporation of Ohio

Application April 29, 1936, Serial No. 62,368

Term of patent 14 years

To all whom it may concern:

Be it known that I, William E. Mackelfresh, Jr., a citizen of the United States and residing at Chicago, in the county of Cook and State of Illinois, have invented a new, original, and ornamental Design for an Ashtray, of which the following is a specification, reference being had to the accompanying drawing, forming a part thereof.

The figure is a perspective view of an ashtray showing my new design.

I claim:

The ornamental design for an ashtray substantially as shown.

WILLIAM E. MACKELFRESH, JR.
